UNITED STATES PATENT OFFICE.

LEONARD JAMES GLOSTER, OF BIRMINGHAM, ENGLAND.

DECORATIVE MATERIAL FOR ORNAMENTAL PANELS, PLAQUES, OR THE LIKE.

Application filed June 15, 1925. Serial No. 37,018.

To all whom it may concern:

Be it known that I, LEONARD JAMES GLOSTER, a subject of the King of Great Britain, of 33 Hockley Hill, Birmingham, 5 England, have invented certain new and useful Improvements in and Relating to a Decorative Material for Ornamental Panels, Plaques, or the like, of which the following is a specification.

10 This invention relates to a new or improved decorative material for ornamental panels, plaques, or the like adapted for application to articles of jewelry, clocks, watches, hand-bags, ornamental cases and 15 boxes, brushes, mirrors, toiletware and various other articles:

The object of my invention is to provide simple and inexpensive means whereby the 20 appearance and effect of enamel ornamentation can be very closely imitated.

Enamel for the purpose of ornamentation is generally in the form of a coloured translucent layer applied to a silver or other metal surface which has previously been 25 engine-turned or otherwise treated. The surface so produced is of attractive appearance, but is extremely expensive and is very fragile, as a slight blow or a sudden change in temperature is sufficient to break or crack 30 the enamel.

By my invention a similar effect can be produced very cheaply, and the finished article cannot readily be damaged and is proof against cracking under any conditions 35 to which it is liable to be subjected in use.

A further object of my invention is to provide a decorative material which is of extremely attractive appearance, and can be readily produced in any desired colour 40 or shade, or may be uncoloured if desired or arranged to give the appearance of a transparent enamel over engine-turned gold, silver or other metal.

Another object is to provide a decorative 45 material which can be supplied in panels or sheets of any desired size or shape and bearing any desired pattern. The material is thus made available for a wide variety of different purposes.

50 My invention comprises the manufacture of a decorative material fulfilling these objects by impressing a pattern on a surface of a translucent and flexible sheet and applying to the impressed surface a thin coating 55 of metal or other suitable opaque substance.

Preferably the sheet is of celluloid and the metal backing is sprayed thereon so as to obtain an even and thin coating. The other face of the sheet, which in the finished article is the outer face, is preferably highly polished. Light striking the polished face of the sheet passes through the sheet and is reflected from the impressed and coated back, and the appearance of the 60 sheet is that of an engine-turned metal plate having a surface layer of translucent enamel.

Several features of my invention have been illustrated in the accompanying drawings in order that the manner of carrying it into practice may be made clear.

In these drawings:—

Figure 1, is a section on an enlarged scale of a piece of material made in accordance 70 with my invention.

Figure 2, is a diagrammatic section showing one method of impressing the sheet of material.

Figure 3, is a front elevation of a clock 80 showing one method of utilizing the material.

Figure 4, is a diagrammatic section showing one method of impressing a pattern on the inner surface of a tube.

As shown in Fig. 1 the material consists of a sheet of celluloid or cellulose acetate *a* having a suitable raised or impressed pattern on one face to which is applied a thin coating *b* of metal or other suitable material.

Various methods may be employed for impressing the patterns on the back of the sheet, but in practice I have found the method illustrated in Fig. 2 to be convenient. The desired pattern is engine-turned, engraved or otherwise cut on one face of a flat plate *c* of silver or other metal and this plate is employed as one die of a pair between which the celluloid sheet is pressed in a suitable press and at a suitable temperature, the other die *d* having a smooth polished surface to give a planished surface to the other side of the sheet.

In a common method of manufacturing 100 sheet celluloid the final process is the pressing of the sheet between heated and planished dies, and this process may conveniently be replaced by that described above so that the cost of manufacturing the sheet 110 is not appreciably increased.

On removing the sheet from the dies the

engine-turning will be impressed on one face of the sheet, and this face is then coated with gold, silver, bronze, or other metal by any of the known metal-spraying processes.

5 In one process which is found satisfactory in practice the metal in finely-divided form is mixed with a lacquer or other suitable liquid and is blown onto the surface by air pressure. The same result may also be obtained by the known process of spraying fused metal upon the surface by air pressure.

10 Celluloid sheet of any desired colour or shade may be employed to imitate enamel of any colour and the effect may be varied 15 by employing a sprayed coating of different metals on the back.

15 The finished sheets may be employed for a wide variety of purposes which will be apparent to those familiar with the art. For 20 example, they may form panels for the sides of a hand-bag, fronts for ornamental clocks, linings for cigarette cases, or be inset into the lids and sides of boxes.

25 A clock has been illustrated by way of example in Fig. 3 in which the surround *e* for the clock *f* is formed from a coloured sheet of my improved material coated on its rear surface with silver and enclosed within a suitable silver or other rim *g*. The 30 appearance of the surround is identical with that of coloured enamel on an engine-turned silver plate, and could not be distinguished therefrom except by expert examination.

35 Where a circular sheet of the material is required the engine-turning is preferably of a circular pattern, and where the material is required in tubular form, a pattern may be impressed on the inner surface of the tube in the manner illustrated diagrammatically in Fig. 4.

40 In this case a tube *h* of celluloid or cellulose acetate is enclosed with a cylindrical aperture in a block *j*, the aperture being of such a diameter that the tube may be readily 45 inserted therein.

An expanding mandrel is then inserted 50 into the tube having the periphery of each segment *k* engraved or engine-turned with a suitable pattern and the mandrel is expanded to impress this pattern on the inner 55 surface of the tube. This inner surface is subsequently coated with metal as described above and the resulting tube has the appearance of an engine-turned or engraved metal tube coated with enamel.

The presence of the metal coating on the back of a sheet of celluloid or cellulose acetate does not impair its flexibility, and where the material is employed for lining cigarette 60 cases or the like it may be moulded to any

desired contour by pressing between dies which are warmed to such a temperature as temporarily to render the material plastic, the material regaining its normal elasticity on removal from the dies. 65

I claim:—

1. The manufacture of a decorative material by impressing a pattern upon a surface of translucent and flexible material and applying to the impressed surface a thin 70 coating of opaque material.

2. The manufacture of a decorative material by pressing a sheet of translucent and flexible material between a planished die and a die having a pattern cut on its surface so 75 that one surface of the sheet is impressed with that pattern, and subsequently coating the impressed surface with a thin opaque layer.

3. The manufacture of a decorative material by impressing a pattern upon one surface of a sheet of translucent and flexible material and in coating the impressed surface with a thin layer of metal applied by spraying. 80

4. The manufacture of a decorative material by impressing a pattern upon one surface of a sheet of cellulose material and in coating the impressed surface with a thin layer of metal applied by spraying. 85

5. The method of making a decorative material by expanding a member within a thin-walled tube of translucent and flexible material enclosed within a rigid outer container, the peripheral faces of the expanding member having a pattern cut thereon, which pattern is impressed on the inner surface of the tube, in removing the member and in coating the impressed inner surface with a thin layer of opaque material. 95

6. A decorative material comprising translucent and flexible sheet material, having a pattern impressed on one surface and a thin layer of opaque material applied to the impressed surface. 100

7. A decorative material comprising translucent and flexible sheet cellulose material having a pattern impressed on one surface and planished on the other surface and a thin metallic coating applied to the impressed surface. 110

8. The method of manufacturing a decorative tube of translucent and flexible material by impressing a pattern on the inner surface thereof by means of an expanding member, and by coating the impressed inner surface of the tube with opaque material. 115

In testimony whereof I affix my signature.

LEONARD JAMES GLOSTER.
